UNITED STATES PATENT OFFICE.

JOSEPH L. DIXON, OF DETROIT, MICHIGAN.

POLYPHASE ELECTRIC FURNACE.

1,241,499.

Specification of Letters Patent.

Patented Oct. 2, 1917.

Application filed June 28, 1917. Serial No. 176,971.

To all whom it may concern:

Be it known that I, JOSEPH L. DIXON, a subject of the King of Great Britain, residing at Detroit, county of Wayne, and State 5 of Michigan, have invented certain new and useful Improvements in Polyphase Electric Furnaces, of which the following is a full, clear, and exact description.

The invention, subject of this application, 10 pertains to polyphase electric furnaces, and it has for its object the provision of new and improved means for effecting their regulations.

The apparatus heretofore used for this 15 purpose consists, generally speaking, of current transformers which supply current to solenoids that operate contact making devices which control the rotation of motors in opposite directions and thus raise or lower 20 the electrodes. In this way any deviation from the desired value of the current in any one of the electrodes is supposed to cause the electric motor to so operate as to move the electrode in a direction tending to bring 25 the current back to the desired value.

In actual practice, however, such apparatus gives rise to very imperfect regulation of the electrodes. Let it be assumed, for example, in the case of a 3-phase furnace with 30 three upper electrodes arcing into the bath, that when each electrode is carrying the desired current of 1000 amperes the arc gap between each electrode and the bath is one inch. Then, should one of the electrodes 35 come into actual contact with the bath, not only that particular one, but also the other two electrodes will carry an excessive current. Such current will cause the regulating apparatus to raise not only the electrode 40 which is touching the bath, but also the other two which may be correctly located with relation to the bath.

The improvements which I have devised have for their immediate purpose the overcoming of this objection or defect, and to regulate each electrode, not directly and entirely in accordance with any excess or deficiency of current in that particular electrode, but that each of the latter shall be 50 adjusted at such time, and at such time only, as it may be incorrectly located with respect to the bath.

The means which I employ for the accomplishment of this result are shown in the 55 accompanying drawing, in which—

Figure 1 is a diagrammatic illustration of

the means for regulating one of the electrodes of a three-phase furnace.

Fig. 2 is a vector diagram of the current delivered by one of the transformers, and 60

Fig. 3 is a similar diagram of the current operating one of the solenoids employed.

It may be here pointed out that in order to avoid complication Fig. 1 is made to represent the means for regulating but one of 65 the three electrodes, and that the same means will be used in connection with each of the other two when necessary or desired.

Fig. 1 represents an electric furnace bath D, with three electrodes, A, B, C, arcing into 70 the same and connected with and supplied by current from the coils of a three-phase source E. In each of the supply circuits is a transformer F, G, H, the circuit of the first named including a solenoid K, and 75 those of the other two a solenoid L, which they conjointly energize.

The two solenoids K, L, are mechanically 80 opposed to each other through a beam M, pivoted at N. At one end of this beam is a contact O which, when the beam is shifted from a horizontal position, engages either an upper conducting stop P or a lower conducting stop Q. When engaging the first-named stop P the contact O completes the 85 circuit of an electric motor R and drives it in a direction to raise the electrode C. On the other hand, when the lower stop Q is engaged the motor is reversely rotated and thereby lowers the electrode C. 90

It may be assumed that the transformer F has a ratio of 1000 to 1.73, so that when 1000 amperes of current flow through the electrode C, the solenoid K will be energized by a current of 1.73 amperes. This solenoid 95 has 100 turns.

The transformers G, H are connected with the solenoid L, and the secondary terminals of one are reversed so that the vectors of the secondary currents are not inclined to each 100 other at an angle of 120°, but at an angle of 60°. In this way, when each of the transformers G, H delivers a current of 1.73 amperes, the resultant current energizing the solenoid will be 3 amperes. The ratio of 105 each of the transformers G, H is 1000 to 1.73, and the solenoid is so constructed that when the electrodes A and B are each carrying 1000 amperes, the magnetic resultant of the solenoid is 108 ampere turns, so that it has 110 36 turns.

When each of the electrodes A, B, C is

carrying the desired current of, say, 1000 amperes, then the solenoid K tends to lift its end of the beam M with a force resulting from 173 ampere turns while the solenoid L tends to lift its end of the beam with a force resulting from 108 ampere turns. The first named solenoid therefore exerts a pull in excess of that exerted by the other equivalent to 65 ampere turns. To counteract this excess and maintain the beam in balanced position, a spring or a weight S is attached to the beam under the solenoid K which opposes the upward pull of the latter. It is manifest that the beam M will remain in its balanced position whatever currents may be energizing the two solenoids, provided these are in such proportion that the solenoid K exerts a pull equivalent to 65 ampere turns in excess of that of the solenoid L.

In order now to more readily understand the operation of the apparatus, the currents flowing in the electrodes and the solenoids will be graphically analyzed into their components.

Thus, the current flowing in electrodes C consists of two components, one being the current passing between electrodes B and C, and the other that passing between electrodes A and C. These components may be represented by vectors at 60° from each other, and when the system is balanced and each electrode is carrying 1000 amperes, each component consists of a current 1000/1.73 or approximately 580 amperes. Similarly, the currents in the electrodes A and B each consists of two components differing in phase by 60° , each being approximately 580 amperes.

In like manner the current delivered by the transformer F may be analyzed into two components differing in phase by 60° . When the system is balanced and each electrode is carrying 1000 amperes, the transformer F is delivering a current of 1.73 amperes, the two component currents each being one ampere, and each being derived from the corresponding component current of 580 amperes flowing in the electrode C. This splitting of the current from transformer F into its components is shown in the vector diagram Fig. 2, which will be readily understood to represent by C, B, the component derived from the current passing between electrodes C and B, and by C, A that derived from the current passing between electrodes C and A.

Similarly the vector diagram, Fig. 3, illustrates the current which energizes the solenoid L, split into its components, the several vectors representing the current derived from those passing between the various pairs of electrodes.

Assuming now a constant voltage applied to the electrodes A, B, and C, then the

amount of current flowing into the furnace will depend upon the resistance of the arcs between the electrodes and the bath, and assuming further that the furnace is operating with the three arcs of the same and such resistance that the desired current of 1000 amperes is flowing in each electrode, this would represent the normal conditions of operation.

It may, however, by way of illustration, be assumed that the electrode B drops into actual contact with the bath and that, therefore, the resistance between the electrodes A and B decreases to one-half of its normal value, while as a consequence the current passing between these electrodes increases to twice its normal value. For the same reasons the current passing between B and C becomes of twice its normal value, while that between A and C remains normal.

Referring again to the vector diagrams, it will be observed that when the vectors A B and B C are each increased to twice normal value; the current energizing the solenoid K increases from 1.73 to 2.65 amperes, and the pull of this solenoid is now the result of 265 ampere turns. The current energizing the solenoid L, on the other hand, increases from three to approximately 5.57 amperes, and the pull is now the result of approximately 200.5 ampere turns.

The solenoid K, however, still exerts a pull on the beam in excess of that exerted by the solenoid L, equivalent to 64.5 ampere turns, but as the original excess was 65 ampere turns, the difference of .5 of an ampere turn is negligible and not sufficient to materially affect the balance of the beam M, and therefore the electrode C is not raised as it would be by the form of regulating apparatus usually employed.

Again, and as another illustration, should the electrode B become withdrawn to such an extent from the bath that no current passes through it, then the only current entering the bath is that passing between the two electrodes A and C. In this case the current energizing such of the solenoids K and L is one ampere. Therefore, the excess pull of solenoid K over that which solenoid L exerts, becomes the equivalent of 64 ampere turns instead of the original 65 ampere turns. This difference is not sufficient to disturb the balance of the beam, and hence the electrode C will not be lowered as it would be by the ordinary means of regulation employed.

In a like manner, any increase or decrease of the current through the electrode C, resulting from a variation of the resistance of the arc between electrode A and the bath, will have no effect in raising or lowering of C.

On the other hand, it is manifest that should the resistance of the arcs between A and B

and the bath remain normal, any variation of the current through the electrode C, due to variations in the resistance of its own arc, will cause one of the solenoids K or L to exert an overbalancing pull on the lever M, with the result that electrode C will be either raised or lowered as may be required to increase or decrease the resistance of the arc from it. As indicated above, the system above described may be duplicated for the regulation of the other electrodes A and B, but this is not illustrated in detail for the sake of simplicity.

In the above description of operation I have omitted consideration of the impedance of the system except so far as the resistance of the arcs is concerned. This simplifies the matter merely notwithstanding that both resistance and inductance in the system as a whole affect both the volume and the phase positions of the currents passing between the electrodes and the bath.

It will be understood that the exact relative strengths of the opposing solenoids K and L may be other than those given by way of illustration, and that in many other specific details the apparatus may be greatly modified without departing from the spirit of the invention, which will now be seen to reside, in essence, in the regulation of each electrode in a polyphase furnace by two mechanically opposed magnetic elements, one energized by the current passing through the electrode to be regulated and tending to adjust the same in a direction to decrease the current flow, and the other partially balancing the attractive effort of the first and energized by the resultant of the currents flowing through the other electrodes.

What, therefore, I now claim as my invention is:

1. The combination with any one of the electrodes, of a polyphase electric furnace of regulating means therefor, comprising a magnetic element energized by the current flowing through the said electrode and when operating adapted to decrease the said current, and a partly counterbalancing opposing magnetic element energized by a resultant of the currents flowing through the other electrodes, as set forth.

2. In a polyphase electric furnace, the combination with each electrode therein, of a magnet or solenoid energized by the cur-

rent flowing through such electrode and adapted upon the passage through it of an excessive current to reduce such current flow, and a partly counterbalancing opposing magnet energized by a resultant of the currents flowing through the other electrodes, and adapted when operative to overbalance the effect of the other magnet to increase the flow of current through the first named electrode, as set forth.

3. In a polyphase electric furnace, the combination with each electrode therein, of a magnet or solenoid energized by currents induced from that flowing through the said electrode and adapted on a given increase in the energizing current to reduce the flow of current through the electrode, and a partly counterbalancing opposing magnet or solenoid energized by a resultant of currents induced from those flowing through the other electrodes and adapted when operative to overbalance the effect of the other magnet to increase the current inducing the energizing current of the latter.

4. The combination with any one of the electrodes in a polyphase electric furnace, of a solenoid energized by the current flowing through said electrode, a solenoid of normally less attractive power energized by a resultant of the currents flowing through the other electrodes, a mechanical device controlled by the two solenoids and acted upon by means which compensates for the normal difference in the effects thereof, and means controlled by said device for raising and lowering the regulated electrode according to the solenoid which exerts a preponderating effect.

5. The combination with one of the electrodes, of a polyphase furnace, of a solenoid energized by current flowing through said electrode, a solenoid of lesser power energized by a resultant of the currents flowing through the other electrodes, a pivoted beam oppositely attracted by the two solenoids, a compensating device acting thereon to assist the weaker solenoid to maintain the beam in balance, a circuit controller operated by the movement of the beam, and a motor operated in either direction according to the position of the beam for raising and lowering the said electrode.

In testimony whereof I affix my signature.
JOSEPH L. DIXON.
